FEED-OFF-THE-ARM SEWING MACHINE

Frederick F. Zeier, Stratfield, Conn., assignor to
The Singer Manufacturing Company, Elizabeth, N. J., a corporation of New Jersey

Application March 19, 1948, Serial No. 15,805

19 Claims. (Cl. 112—63)

1

This invention relates to sewing machines, more particularly to the feed-off-the-arm type, and has for an object to provide a machine having a frame contour permitting convenient manipulation and presentation of the work by the operator to the stitching instrumentalities.

Another object of the present invention is to provide a feed-off-the-arm type sewing machine having lightweight but sturdy and well-balanced mechanism for actuating the stitching and feeding devices, adapting the machine for handling heavy work at relatively rapid sewing speeds.

Another object of the present invention is to provide a cylinder-bed sewing machine with an improved feeding mechanism wherein the needle is moved laterally in the line of feed while in the work to assist the usual feed-dog in its work-advancing action.

A further object of the present invention is to provide a feed-off-the-arm sewing machine having a work-arm of small cross-section at its free end, whereby tubular articles of small diameter can be stitched.

The present invention also aims to provide for convenient initial assembly of the parts and for ready accessibility of the same for inspection, adjustment and repair.

With the above and other objects in view, as will hereinafter appear, the invention comprises the devices, combinations and arrangements of parts hereinafter described and particularly pointed out in the claims.

In the drawings which illustrate a preferred embodiment of the invention,

Fig. 1 is a perspective view of the improved machine.

Fig. 2 represents a vertical sectional view taken longitudinally of the head and its supporting bracket-arm, showing the needle-bar and its actuating connections with the rotary arm-shaft of the machine.

Fig. 3 is a front elevation of the machine with the upper lateral arm and depending arm in vertical section.

Fig. 4 is a left side elevation of the machine with the face-plate removed; the depending arm and the work-supporting arm being shown in vertical section.

Fig. 5 represents an enlarged sectional view of the feed-advance rocker and taken substantially along the line 5—5, Fig. 4.

Fig. 6 is a right side elevation of the machine with the side cover-plate removed from the standard to show the belt connection between the rotary arm-shaft and the counter-shaft.

Fig. 7 is a top plan view of the work-support-

ing arm with the cover-plates removed and the lower end-portion of the depending arm in section, showing the feed-dog and its actuating connections within the work-supporting arm.

Fig. 8 is a view similar to Fig. 7, but showing only that part of the looper mechanism which is within the work-supporting arm.

Fig. 9 is an enlarged horizontal sectional view taken substantially along the line 9—9, Fig. 3, illustrating the manner in which the looper actuating rock-shafts in the depending arm are operatively connected to the counter-shaft in the laterally extending arm.

Fig. 10 represents an enlarged vertical sectional view of the work-arm and taken substantially along the line 10—10, Fig. 4.

Fig. 11 represents an enlarged vertical sectional view of the work-arm and taken substantially along the line 11—11, Fig. 4.

Fig. 12 is a perspective view of the looper-carrier bar fulcrum-block and its retainer.

Fig. 13 is an enlarged vertical sectional view of the work-arm and taken substantially along the line 13—13, Fig. 8.

Fig. 14 is a right side elevation, on a reduced scale, of the machine, showing the louvers in one of the side cover-plates.

The detailed description which follows is broken down into sections in order to facilitate a quick understanding of the various mechanisms of the machine and their operations. It should be understood that the present invention is not limited to the details of construction and arrangement of parts illustrated in the accompanying drawings, for it is capable of other embodiments which come within the scope of the appended claims.

Machine-frame

The machine-frame, in its preferred embodiment, comprises a standard 20 of a bracket-arm 21 having at its overhanging end a head 22. Preferably integral with the front side of the standard 20 is the work-arm casting comprising an upper forwardly projecting arm 23, a laterally extending arm 24, and a vertically depending arm 25 carrying a horizontal work-supporting cylinder-bed or arm 26 disposed so that its free end underlies the head 22. The forwardly extending arm 23 of the work-arm casting is substantially C-shaped in cross-section to provide a belt-compartment 27 and is ribbed, as at 28 (Fig. 6) for strength. Secured to seats 29 and 30 (Fig. 2), by the screws 31 and 32, is a weighted base- or foot-member 33 offset laterally at its lower end to provide a more substantial machine-

55

base and to counterbalance the unsupported overhang of the machine. The open face of the C-shaped forwardly extending arm 23 is adapted to be closed by a side cover-plate 34, the lower portion of which is provided with louvers 35 for permitting the ingress of air to be circulated throughout the work-supporting arm 26.

The work-supporting arm 26 is preferably made exceedingly small in cross-sectional area at its free end, in order that tubular articles of small diameter can be sewn on the machine. The arm 26 is preferably U-shaped in cross-section and is designed to be detachably secured to the lower end of the depending arm 25. As will be seen in Figs. 1 and 4, the work-supporting arm 26 is secured against a horizontal seat 36 provided on the bottom of a lateral flange 37 integral with the depending arm 25; the screws 38 and locating pins 39 (Fig. 1) fastening the work-supporting arm to the depending arm in its proper aligned position. Integral with the lower end of the depending arm 25 is a downwardly projecting extension 40 (Figs. 3 and 4) normally disposed within a chamber 41 provided in the enlarged end of the work-supporting arm 26, said extension providing a support for the bearing bushings 42, 43 and 44 in which are journaled the rock-shafts, later to be described, housed within the depending arm 25. One of the advantages of having the shafts within the depending arm supported in bearings all of which are carried by said arm is that the mechanisms in the depending arm 25 and the work-supporting arm 26 can be separately assembled in their respective arms and then the work-supporting arm can be attached to the depending arm as a unit. Suitable cover-plates 45 and 46 are provided upon the work-supporting arm 26 to afford access to the mechanism within the chamber 41 in the work-supporting arm, and to enable interconnecting the depending-arm mechanism with the work-supporting arm mechanism. Cover-plate 45 is provided with a transparent window 47 through which the lever of the oil in the chamber 41 can be seen. Cover-plate 46 is provided with a drain-plug 48 which can be removed when it is desired to drain the oil out of the chamber 41.

The open top of the work-supporting arm 26, beyond the depending arm 25, is adapted to be closed by a cover-plate 49 having a conventional attachment slideway 50, and a throat-plate 51 through which the needles and the feed-dog operate. Access to the loopers within the free end of the work-supporting arm 26 is gained through the side opening 52 closed by the swinging gate 53 (Figs. 1, 7 and 8) carried on a retractable slide 54 mounted in the bottom wall of the work-supporting arm 26. Louvers 55 in the swinging gate 53 provide openings for the egress of air and lint from within the work-supporting arm 26.

As will be observed in Fig. 3, the depending arm has its lower portion, immediately above the flange 37, formed narrower than the width of the work-supporting arm 26 beneath it for the purpose of providing a maximum amount of clearance space for the manipulation of the work.

In the machine illustrated, driving power is adapted to be applied from any suitable source, preferably from beneath the supporting table-structure (not shown), through a belt 56 adapted to run on a drive pulley 57 mounted on the inner end of a rotary main- or arm-shaft 58 journaled in antifriction bearings 59 and 60 carried in the bracket-arm 21. The main-shaft 58 is connected by a clip-belt 61 to a rotary counter-shaft 62

journaled in antifriction bearings 63 and 64 carried in the laterally extending arm 24. Secured to the exposed inner end of the counter-shaft 62 is a hand-wheel 65 which is within easy reach of the operator. To provide an effective guard for the driving belt 56, there is provided a side cover-plate 66 which houses the belt and the drive pulley 57.

As will be seen in Fig. 1, there are provided upon the laterally extending arm 24 a top cover-plate 67 and a side cover-plate 68 closing openings through which the mechanism within said arm 24 is rendered accessible.

From the above description, it will be understood that a machine-frame is provided in which the stitching zone at the free end of the work-supporting arm 26 is very accessible to the operator from the work-presentation point of view and that good visibility is afforded the operator in manipulating the work. Particular notice is called to the arrangement of the weighted foot-portion or base 33. When viewing the machine from the front, it will be appreciated that a major portion of the weighted foot-portion 33 is disposed to the right of the forwardly projecting arm 23 and that the bracket-arm 21, laterally extending arm 24 and work-supporting arm 26 are disposed to the left of the arm 23. This arrangement approximates a balanced set-up and facilitates supporting the machine with its standard 28 adjacent the edge of the table (not shown) so that the work-supporting arm 26 is sustained in mid-air with ample free space on opposite sides thereof for the handling of the work.

Needle-bar mechanism

The needle-bar mechanism of the present machine is constructed substantially in accordance with the disclosure in my United States Patent No. 2,329,681, issued September 14, 1943. For the sake of brevity, only such reference will be made to the needle-bar mechanism as will give a clear understanding of the operation thereof in the present machine.

Referring to Figs. 2 and 4, it will be observed that the rotary main- or arm-shaft 58 has secured to its outer end a needle-bar actuating crank 69 connected by a depending link 70 to a needle-bar 71 carrying at its lower end the needles 72. The needle-bar 71 is journaled for endwise reciprocation in bearing bushings provided in the spaced arms 73 and 74 of a substantially C-shaped needle-bar-frame 75 formed preferably of aluminum, magnesium or other light-weight material and provided with a horizontally projecting fulcrum-rod 76 mounted for oscillation in an extended lug 77 preferably formed integral with the machine-head 22. In the present machine, the fulcrum-axis of the needle-bar-frame 75 is horizontally transverse to the length of the work-supporting arm 26 and therefore the needles 72 are sidewise vibrated lengthwise of said arm 26. The endwise reciprocatory and sidewise vibratory movements of the needles 72 are timed so that the needles move sidewise toward the free end of the arm while the needles are in the work. Oscillations are imparted to the needle-bar-frame 75 about the axis of the fulcrum-rod 76 through mechanism comprising a rearwardly and upwardly curved rock-lever 78 preferably clamped at its lower end upon the reduced end-portion of the fulcrum-rod 76. At its upper end, the rock-lever 78 is connected to one end of a relatively short pitman 79 formed at its other end with a

strap 80 embracing an adjustable eccentric 81 secured to rotate with the rotary arm-shaft 58.

It will be understood from the foregoing that as the arm-shaft 58 is rotated the eccentric 81 actuates the pitman 79 which in turn operates the rock-lever 78 to oscillate the needle-bar-frame 75. The extent of oscillatory movement imparted to the needle-bar-frame is dependent upon the amount of eccentricity of the eccentric 81, and in order to vary the amplitude of the oscillatory movements of the needle-bar-frame 75 the eccentric is made adjustable. A detailed description of the constructive features of the adjustable eccentric 81 will not herein be given for the reason that the same is fully described in the U. S. patent of W. Myers, No. 2,128,031, dated August 23, 1938.

To effect adjustment of the eccentric 81, the top of the bracket-arm 21 has mounted therein a detent 82, the details of construction of which are similar to those illustrated in the U. S. patent of W. Myers, No. 2,063,264, dated December 8, 1936. When it is desired to adjust the amplitude of oscillation of the needle-bar-frame 75, the detent 82 is depressed until the lower end thereof enters a stop notch 83 (Fig. 2) in the adjusting member 84 of the eccentric 81, after which, if desired, the detent can be partly rotated and locked in depressed position. With the adjusting member 84 of the eccentric 81 thus latched against turning, suitable manual turning of the arm-shaft 58 will effect the desired adjustment of the eccentric 81.

Presser mechanism

The presser mechanism of the present machine is best shown in Figs. 2 and 4. Referring to these figures, it will be observed that there is journaled for endwise movement in spaced lugs 85 and 86 on the machine-head 22 a presser-bar 87 carrying at its lower end a presser-foot 88. At its upper end, the presser-bar 87 has clamped thereon a split collar 89 (Fig. 4) having a laterally projecting guide-lug 90 adapted to extend through a suitable slot provided in the side wall of the machine-head 22, whereby the presser-bar 87 is prevented from turning in its bearings. Also formed on the collar 89 are a pair of upstanding ears 91, 92 carrying between them a roller 93 which is engaged by the free end of a leaf-spring 94 mounted to bias the presser-bar 87 yieldingly downwardly. The pressure of the spring 94 is regulated by a screw 95 threaded through the bracket-arm 21. The roller 93 is employed to minimize any side pressure exerted by the presser-bar 87 on its bearings resulting from the action of the leaf-spring 94 on the top of the presser-bar.

The presser-bar 87 is adapted to be raised by means of the usual hand-operated lifting-lever 96 which is pivoted on a screw 97 threaded into the lug 85; the lifting-lever 96 being disposed to contact the head of the collar clamping screw 98. Treadle-controlled means are also provided for raising and lowering the presser-foot. This means is shown, in part, in Fig. 4 and comprises a pivotally supported lever 99 to which is connected a depending link 100 whose lower end is apertured to receive the presser-bar guide-lug 90. The lever 99 is connected by suitable means to a knee- or foot-operated treadle (not shown).

Four-motion feeding mechanism

The four-motion feeding mechanism of the present machine is adapted to operate in unison with the needle-feed previously described in advancing the work off the free end of the work-

supporting arm 26. This four-motion feed, showing in Figs. 3, 4, 7, 9 and 10, comprises a feed-dog 101 having needle-apertures 101' through which the needles operate. The feed-dog is supported by a rearwardly extending tail or shank 102 adjustably secured, as by screws 103, upon the forward end-portion of a feed-bar 104. The feed-bar 104 extends lengthwise of the work-supporting arm 26 and is lengthwise slidably and crosswise pivotally mounted on bearing blocks 105 embracing an eccentric pin 106 mounted within the opposite side walls of the work-supporting arm. To facilitate assembly, the open bottomed slot 107 in the feed-bar 104 in which the bearing blocks 105 are disposed is closed by a bridge-bar 108 (Figs. 10 and 11) fastened by screws 109 threaded into said feed-bar. It will be appreciated that the eccentric pin 106 is provided for the purpose of regulating the height of the ser-

rated work-engaging face of feed-dog 104 relative to the upper surface of the throat-plate 51. Access to the eccentric pin 106 is gained through a clearance opening 110 provided in the side wall of the work-supporting arm 26, the eccentric pin 106 being retained against endwise shift and accidental turning by a screw 111 (Fig. 10) threaded into the side wall of the work-supporting arm 26 and having its inner end seated in an annular recess 112 provided beneath the head of the eccentric pin.

The rear end-portion of the feed-bar 104 lies directly beneath the vertically depending arm 25 of the machine frame, which arm contains the feed-dog lifting and advance-and-return mechanisms. The feed-dog lifting mechanism derives its actuation from an eccentric 113 fast on the rotary counter-shaft 62. Embracing this feed-lift eccentric 113 is the strap 114 of a vertical pitman 115 connected at its lower end to a rocker 116 (Fig. 5) journaled on a fulcrum-rod 117 fixed in the side walls of the depending arm 25. Connected to the rocker 116 is the upper end of a depending link 118 connected at its lower end and within the chamber 41 to the forked end of the feed-bar 104. Rotation of the counter-shaft will cause the eccentric 113 to impart to the pitman 115, rocker 116 and link 118 rising and falling movements which are transmitted to the feed-bar 104 and effect a rocking of the feed-bar about the longitudinal axis of the eccentric pin 106. It will be understood that the amplitude of movement imparted to the feed-dog 101 is constant and that the effective portion of the feed-dog lift above the level of the throat-plate 51 is regulated by the eccentric pin 106.

The feed advance-and-return motions of the feed-dog 101 are obtained from an adjustable eccentric 119 which is also mounted on the counter-shaft 62. The details of construction of this eccentric are identical with those of eccentric 81 mounted on the arm-shaft 58. Embracing the eccentric 119 is the strap 120 of a forwardly extending pitman 121 (Figs. 3, 4 and 9) connected at its other end to the upper arm of a two-arm rock-lever 122 journaled intermediate its ends on a fulcrum-bar 123 fixed in the side walls of the depending arm 25. The lower arm of the rock-lever 122 is fitted with a cylindrical pin 124 which slidably projects into a substantially vertically disposed aperture formed in a horizontal pin 125 journaled for free turning movement in the forked end of the feed-bar 104 just forward of the feed-lift connection. Rotation of the counter-shaft 62 will impart to the rock-lever 122, through the adjustable eccentric 119, rock-

ing movements about the fulcrum-bar 123, and these rocking movements will effect an advance and return of said feed-bar 104.

To provide for adjusting the stitch-length of the feed-dog 101, the laterally extending arm 24 (Fig. 3) is fitted with a spring retracted detent 126 which when depressed by the operator is adapted to enter a stop-notch 127 formed in the eccentric adjusting member 128. With the adjusting member 128 thus latched against turning, manual rotation of the counter-shaft 62 will effect the desired adjustment of the eccentric 119.

In the machine shown in the drawings the upper or needle-feed and the lower four-motion feed each derives its work-advancing movements from independent adjustable eccentrics and, therefore, when changing the stitch-length, it is essential that the two eccentrics be adjusted in unison. To accomplish this in the present machine, the balance-wheel 65 is manually turned until the detent 82 on the bracket-arm 21 registers with the stop-notch in the eccentric 81 of the needle-feed mechanism, in which position the detent is depressed and turned, thereby locking the same in latching position. This leaves one hand of the operator free so that the detent 126 for the eccentric 119 of the lower feeding mechanism may be manually depressed into locking position while the balance-wheel 65 is turned with the other hand of the operator until the required amount of eccentricity has been obtained. To resume sewing the detent 126 is released, as is also the detent 82. It will be appreciated that the two detents provide means whereby the two eccentrics 81 and 119 may be concomitantly adjusted to vary the eccentricities thereof.

Looper mechanism

The stitch-forming mechanism of the present machine is adapted to produce conventional two-thread chain-stitches and includes a pair of thread-carrying loopers 129 which undergo sidewise as well as loop-seizing and loop-shedding motions. The loopers 129 are secured to a swing-out carrier 130 which is pivoted, as at 131 (Fig. 4), on one end of a looper-bar 132 pivotally and slidably carried within the work-supporting arm at a point intermediate the ends of the looper-bar. The means pivotally and slidably supporting said looper-bar 132 preferably includes a pair of fulcrum-blocks 133, 134 (Figs. 8 and 11) formed to embrace the sides of the looper-bar 132 and having cylindrical peripheries fitted into a cylindrical seat 135 bored into the side walls of the work-supporting arm 26. As will be seen in Fig. 11, the two fulcrum blocks 133 and 134 are held in their proper position by two retainers 136, 137 which are fastened directly to the side walls of the work-supporting arm 26 by the screws 138 and 139. It will be understood that the looper-bar 132 can slide endwise relative to the fulcrum-blocks 133 and 134, and that the fulcrum-blocks can turn in their seat 135, thus to permit the loopers 129 to be moved sidewise.

The looper-bar 132 at its looper supporting end is steadied in its movement by opposed hardened and ground guide-plates 140 and 141 (Figs. 2 and 4). The guide-plate 140 is secured by screws 142 to the bottom of a needle-guide 143 which is attached by screws 144 to the side wall of the work-supporting arm 26, while the guide-plate 141 is secured by screws 145 upon the bottom wall of the work-supporting arm. Adjacent its inner end, the looper-bar 132 is guided by a bearing-

block 146 which is secured by screws 147 to the work-supporting arm 26. The guide-plates 140 and 141 and the bearing-block 146 maintain the looper-bar 132 adequately supported at both ends thereof.

The mechanism for imparting loop-seizing and -shedding and sidewise or "needle-avoiding" movements to the loopers 129 is contained within the vertically depending arm 25 of the machine. It will be understood that the loopers 129, in advancing to enter the needle-thread-loops presented by the needles 72, travel endwise of the work-supporting arm 26 in a direction opposite to the direction of feed. In Fig. 9 it will be observed that the counter-shaft 62 is preferably formed with a crank 148 connected by a short pitman 149 to one end of a rock-arm 150 clamped upon the upper end of a vertically disposed looper-actuating rock-shaft 151 journaled at its opposite ends in the top and bottom walls of the depending arm 25. Adjacent its lower end, the looper-actuating rock-shaft 151 has suitably secured to it a rock-arm in the form of a cylindrical pin 152 (Fig. 8), the free end of which slidably projects into an aperture formed in a vertical pin 153 journaled for free turning movement in the bifurcated end of the looper-bar 132. Rotation of the crank 148 will effect an oscillation of the rock-shaft 151, which in turn will impart an endwise movement to the looper-bar 132 giving to the loopers 129 their loop-seizing and loop-shedding strokes.

Sidewise movements of the loopers 129 are derived from an eccentric 154 (Fig. 9) fast on the counter-shaft 62. This eccentric 154 is connected by a pitman 155 to one end of a rock-lever 156 of which the other end is clamped to the upper end of a second vertically disposed looper-actuating rock-shaft 157 journaled at its opposite ends in the top and bottom walls of the depending arm 25. Clamped to the rock-shaft 157, adjacent its lower end, is a rock-arm 158 which is connected by a link 159 to the bifurcated end of the looper-bar 132. Rotation of the eccentric 154 will transmit oscillation to the rock-shaft 157 which, through the rock-arm 158 and link 159, will impart sidewise movements to the looper-bar 132. Thus, the loopers 129 carried by the looper-bar are moved sidewise in proper timed relation with their endwise loop-seizing and loop-shedding movements; the combined motions resulting in a "four motion" travel of the loopers 129.

It will be observed by referring to Fig. 4 that the looper-bar 132 and its actuating elements within the base of the depending arm and including the rock-arms 152 and 158 and the link 159, are disposed in substantially the same horizontal plane. This is advantageous for the reason that the looper-bar is not subjected to any vertical forces tending to bind the looper-bar in its supports or to displace the loopers 129 out of their horizontal plane of travel. Also, it simplifies the supports for the looper-bar 132 and makes for a freely operating mechanism.

Spreader mechanism

To assist in stitch-formation, the loopers 129 have cooperating therewith a spreader device 70 which is adapted to distend the looper-thread to form the usual triangle with the previous needle-thread-loop for entrance by the descending needle. The spreader device comprises an angular member 160 (Figs. 4, 8 and 13) having formed in the under face of its free end a pair of thread-

engaging notches disposed so that when the spreader moves transversely of the work-arm 26 the spreader engages one limb of the looper-thread and spreads it. The shank of the angular member 160 is adjustably secured to an arm 161 by screws 162 and 163, screw 163 serving as a fulcrum-screw pivotally supporting the spreader device on an angle-bracket 164 fastened by the screws 165 (Fig. 13) to the side wall of the work-supporting arm 26. The spreader device is caused to pivot about the fulcrum-screw 163 by a cam-block 166 on the looper-bar 132, which cam-block is formed with an arcuate cam-groove entered by a roller 167 carried by the arm 161 of the spreader device. Actuation of the spreader from a cam on the looper-bar insures proper timing between the looper and the spreader.

Having thus set forth the nature of the invention, what I claim herein is:

1. In a feed-off-the-arm sewing machine having a frame provided with an overhanging head and a work-supporting arm having its free end disposed beneath said head, an endwise reciprocating needle-bar journaled in said head and mounted for lateral work-feeding movements in a plane parallel to the vertical plane of the axis of the work-support, means for imparting said lateral work-feeding movements to said needle-bar, and looper mechanism in said work-supporting arm complementary to said needle in the formation of chain-stitches.

2. In a feed-off-the-arm sewing machine having a frame provided with an overhanging head and a work-supporting arm having its free end disposed beneath said head, an endwise reciprocating needle-bar journaled in said head and mounted for lateral work-feeding movements in a plane parallel to the vertical plane of the axis of the work-support, means for imparting said lateral work-feeding movements to said needle-bar, and stitch-forming mechanism in said work-supporting arm including a looper complementary to said needle in the formation of chain-stitches, and actuating connections for imparting to said looper loop-seizing movements endwise of said work-supporting arm.

3. In a feed-off-the-arm sewing machine having a frame provided with an overhanging head and a work-supporting arm having its free end disposed beneath said head, a needle-bar journaled in said head for work-penetrating endwise and work-feeding sidewise movements, a needle carried by said needle-bar, means for imparting said endwise and sidewise movements to said needle-bar, work-feeding mechanism in said arm including a feed-dog for advancing work lengthwise of the work-arm towards its free end and in unison with the work-feeding sidewise movements of said needle, and stitch-forming mechanism in said work-supporting arm complementary to said needle in the formation of chain-stitches, said stitch-forming mechanism including a looper having loop-seizing movements in a direction opposed to the direction of feed.

4. In a feed-off-the-arm sewing machine having a frame provided with an overhanging head and a work-supporting arm having its free end disposed beneath said head, a needle-bar journaled in said head for work-penetrating endwise movements and work-feeding sidewise movements lengthwise of said work-supporting arm, feeding mechanism in said work-supporting arm including a feed-dog having work-advancing movements lengthwise of said work-supporting arm and operating in unison with said needle,

and looper mechanism including a threaded looper in said work-supporting arm complementary to the needle in the formation of two-thread chain-stitches.

5. In a feed-off-the-arm sewing machine having a frame including a bracket-arm terminating in a head, a first rotary shaft journaled in said bracket-arm, a second rotary shaft, a driving connection between said shafts, a work-supporting arm having its free end disposed beneath said bracket-arm head, an arm supporting said work-supporting arm and providing bearings in which said second rotary shaft is journaled, an endwise reciprocating and sidewise vibratory needle-bar supported in said head, actuating devices connecting said needle-bar to said first rotary shaft, lower stitch-forming mechanism in said work-supporting arm complementary to said needle in the formation of chain-stitches, and actuating connections between said lower stitch-forming mechanism and said second rotary shaft.

6. In a feed-off-the-arm sewing machine having a frame including a bracket-arm terminating in an overhanging head, and a work-supporting portion including a depending arm having a downwardly projecting extension and a work-supporting arm carried by said depending arm and housing said extension, a needle-bar journaled for endwise reciprocating movement in said head, lower stitch-forming and work-feeding devices in said work-supporting arm, a rotary main-shaft, actuating shafts journaled in said depending arm in bearings provided in said downwardly projecting extension, and operative connections between said rotary main-shaft and said actuating shafts.

7. A cylinder-bed sewing machine having, a frame including a bracket-arm terminating in an overhanging head, and a work-supporting portion including a depending arm and a work-supporting arm carried by said depending arm with its free end beneath said overhanging head, an endwise reciprocating needle-bar journaled in said head, a needle carried by said needle-bar, work-feeding mechanism operating in timed relation with said needle, a rotary shaft journaled in said frame, a pair of actuating shafts journaled in said depending arm, driving connections between said actuating shafts and said rotary shaft, a movable looper complementary to said needle in the formation of chain-stitches, a looper-bar carrying said looper and movable in a single plane, and operating connections between said actuating shafts and said looper-bar, said connections disposed and movable in a single plane.

8. A cylinder-bed sewing machine having, a frame including a bracket-arm terminating in an overhanging head, and a work-supporting portion including a depending arm and a work-supporting arm carried by said depending arm with its free end beneath said overhanging head, an endwise reciprocating needle-bar journaled in said head, a needle carried by said needle-bar work-feeding mechanism operating in timed relation with said needle, a rotary shaft journaled in said frame, a pair of rock-shafts journaled in said depending arm, driving connections between the upper ends of said rock-shafts and said rotary shaft, a movable looper complementary to said needle in the formation of chain-stitches, a looper-bar extending lengthwise of said work-supporting arm and carrying said looper, means supporting said looper-bar for pivotal and slidable movements in a fixed plane, and operating ele-

11

ments connecting each of said rock-shafts to said looper-bar, said elements disposed and movable in the plane of movement of said looper-bar.

9. A cylinder-bed sewing machine having, a frame including a bracket-arm terminating in an overhanging head, and a work-supporting portion including a depending arm and a work-supporting arm carried by said depending arm with its free end beneath said overhanging head, an endwise reciprocatory needle-bar journaled in said head, a needle carried by said needle-bar work-feeding mechanism operating in timed relation with said needle, a rotary shaft journaled in said frame, a pair of rock-shafts journaled in said depending arm, driving connections between the upper ends of said rock-shafts and said rotary shaft, a movable looper complementary to said needle in the formation of chain-stitches, a looper-bar extending lengthwise of said work-supporting arm and carrying said looper, means supporting said looper-bar for pivotal and slideable movements in a fixed plane, a rock-arm secured at one end to one of said rock-shafts and operatively associated with said looper-bar, a rock-arm secured to the other of said rock-shafts, and a link connecting said last-named rock-arm to said looper-arm.

10. A cylinder-bed sewing machine having, a frame including a bracket-arm terminating in an overhanging head, and a work-supporting portion including a depending arm and a work-supporting arm carried by said depending arm with its free end beneath said overhanging head, an endwise reciprocatory needle-bar journaled in said head, a needle carried by said needle-bar work-feeding mechanism operating in timed relation with said needle, a rotary shaft journaled in said frame, a pair of rock-shafts journaled in said depending arm, driving connections between the upper ends of said rock-shafts and said rotary shaft, a movable looper complementary to said needle in the formation of chain-stitches, a looper-bar extending lengthwise of said work-supporting arm and carrying said looper, means supporting said looper-bar for pivotal and slideable movements in a fixed plane, a rock-arm secured at one end to one of said rock-shafts and having a cylindrical portion slidably associated with said looper-bar, a rock-arm secured to the other of said rock-shafts, and a connection between said last-named rock-arm and said looper-bar.

11. In a feed-off-the-arm sewing machine having, a frame including a bracket-arm terminating in an overhanging head, and a work-supporting portion including a depending arm having a work-supporting arm carried thereby, an endwise reciprocatory needle-bar journaled in said head and mounted for lateral work-feeding movements in a plane parallel to the vertical plane of the axis of the work-support, means for imparting reciprocating and lateral work-feeding movements to said needle-bar, a movable looper complementary to said needle in the formation of chain-stitches, a looper-bar extending lengthwise of said work-supporting arm and carrying said looper, a rotary shaft journaled in said frame, a pair of rock-shafts journaled in said depending arm and operatively connected with said rotary shaft, and means connecting said rock-shafts with said looper-bar for actuating the latter element.

12. In a feed-off-the-arm sewing machine having, a frame including a bracket-arm terminating in an overhanging head, and a work-supporting portion including a depending arm having a

12

work-supporting arm carried thereby, an endwise reciprocatory needle-bar journaled in said head and mounted for lateral work-feeding movements in a plane parallel to the vertical plane of the axis of the work-support, means for imparting reciprocating and lateral work-feeding movements to said needle-bar, a movable threaded looper complementary to said needle in the formation of chain stitches, a looper-bar extending lengthwise of said work-supporting arm and carrying said looper, means pivotally supporting said looper-bar, a rotary shaft journaled in said work-supporting portion, a pair of rock-shafts journaled within and lengthwise of said depending arm and operatively connected with said rotary shaft, and means connecting said rock-shafts with said looper-bar for actuating the latter element thereby to cause the looper, in co-operation with the looper-bar supporting means, to move in a direction parallel to that of the work-feed during its loop-seizing and loop-shedding strokes.

13. In a feed-off-the-arm sewing machine having, a frame including a bracket-arm terminating in an overhanging head, and a work-supporting portion including a depending arm having a work-supporting arm carried thereby, and endwise reciprocatory needle-bar journaled in said head and mounted for lateral work-feeding movements in a plane parallel to the vertical plane of the axis of the work-support, means for imparting reciprocating and lateral work-feeding movements to said needle-bar, a movable threaded looper complementary to said needle in the formation of chain stitches, a looper-bar extending lengthwise of said work-supporting arm and carrying said looper, means supporting said looper-bar for pivotal movements about an axis disposed in parallelism with the general direction of needle reciprocation and slideable movements in a fixed plane disposed at right angles to said pivotal axis, a rotary shaft journaled in said work-supporting portion, a pair of rock-shafts journaled within and lengthwise of said depending arm and operatively connected with said rotary shaft, a rock-arm secured at one end to one of said rock-shafts and operatively associated with said looper-bar, a rock-arm secured to the other of said rock-shafts, and a link connecting said last-named rock-arm to said looper-arm, said rock-shafts and their associated mechanism being adapted to cause the looper, in co-operation with said looper-bar supporting means, to move in a direction parallel to that of the work-feed during its loop-seizing and loop-shedding strokes.

14. In a feed-off-the-arm sewing machine having, a frame including a bracket-arm terminating in an overhanging head, and a work-supporting portion including a depending arm having a work-supporting arm carried thereby, an endwise reciprocatory needle-bar journaled in said head and mounted for lateral work-feeding movements in a plane parallel to the vertical plane of the axis of the work-support, means for imparting reciprocating and lateral work-feeding movements to said needle-bar, a movable looper complementary to said needle in the formation of chain stitches, a looper-bar extending lengthwise of said work-supporting arm and carrying said looper, a rotary shaft, a pair of rock-shafts journaled in said depending arm and operatively connected with said rotary shaft, means connecting said rock-shafts with said looper-bar for actuating the latter element, a feed-bar

pivotedly and slidably supported lengthwise of said work-supporting arm, a feed-dog mounted on one end of said feed-bar for cooperating with said needle in the feeding of the work, and means connecting said feed-bar to said rotary shaft for actuating said feed-bar in proper synchronism with the work-feeding movement of said needle.

15. In a feed-off-the-arm sewing machine having, a frame including a bracket-arm terminating in an overhanging head, and a work-supporting portion including a depending arm having a downwardly projecting extension and a work-supporting arm removably carried upon said depending arm and housing said extension, a needle-bar journaled for endwise reciprocatory movement in said head, a needle carried by said needle-bar, a rotary shaft journaled in said work-supporting portion, a pair of rock-shafts journaled lengthwise within said depending arm with the lower end portions journaled within said downwardly projecting extension, means connecting the upper portions of said rock-shafts with said rotary shaft, a movable looper complementary to said needle in the formation of chain-stitches, a looper-bar extending lengthwise of said work-supporting arm and carrying said looper, means supporting said looper-bar for pivotal and slidable movements in a fixed plane, a pair of rock-arms of which each is secured at one end to respective one of said rock-shafts at a location between the upper end of the rock-shaft and said downwardly depending projection, and means operatively connecting each of said rock-arms with said looper-bar for actuating the latter.

16. In a feed-off-the-arm sewing machine having, a frame including a bracket-arm terminating in an overhanging head, and a work-supporting portion including a depending arm having a downwardly projecting extension and a work-supporting arm removably carried upon said depending arm and housing said extension, a needle-bar journaled for endwise reciprocatory movement in said head, a needle carried by said needle-bar, a rotary shaft journaled in said work-supporting portion, a pair of rock-shafts journaled lengthwise within said depending arm with the lower end portions journaled within said downwardly projecting extension, a movable threaded looper complementary to said needle in the formation of chain-stitches, a looper-bar extending lengthwise of said work-supporting arm and carrying said looper, means supporting said looper-bar for pivotal movements about an axis disposed in parallelism with the general direction of needle reciprocation and slidable movements in a fixed plane disposed at right angles to said pivotal axis, a rock-arm secured at one end to one of said rock-shafts and operatively associated with said looper-bar, a rock-arm secured to the other of said rock-shafts, and a link connecting said last-named rock-shaft to said looper-arm, said rock-shafts and their associated mechanism being adapted to cause the looper, in cooperation with said looper-bar supporting means, to move in a direction parallel to the longitudinal axis of said work-supporting arm during its loop-seizing and loop-shedding strokes.

17. A feed-off-the-arm sewing machine having, a frame including a bracket-arm terminating in a head, a work-arm casting including a forwardly extending arm, a laterally extending arm, and an arm depending downwardly from said laterally extending arm and having a downwardly projecting extension, and a work-sup-

porting arm removably carried by said depending arm and housing said extension, an endwise reciprocatory needle-bar journaled in said head, a needle carried by said needle-bar, a first rotary shaft journaled within said bracket-arm for actuating said needle-bar, a second rotary shaft journaled within said laterally extending arm and operatively connected to said first rotary shaft, a pair of rock-shafts disposed lengthwise of and within said depending arm at opposite sides of said second rotary shaft, said rock shafts each being operatively connected with said second rotary shaft and having its lower end journaled within said downwardly projecting extension, a movable looper complementary to said needle in the formation of chain-stitches, a looper-bar extending lengthwise of said work-supporting arm and carrying said looper, means supporting said looper-bar for pivotal and slidable movements in a fixed plane, a pair of rock-arms of which each is secured at one end to respective one of said rock-shafts at a location between the upper end of the rock-shaft and said downwardly depending projection, and means operatively connecting each of said rock-arms with said looper-bar for actuating the latter.

18. A feed-off-the-arm sewing machine having, a frame including a bracket-arm terminating in a head, a work-arm casting including a forwardly extending arm, a laterally extending arm, and an arm depending downwardly from said laterally extending arm and having a downwardly projecting extension, and a work-supporting arm removably carried by said depending arm and housing said extension, an endwise reciprocatory needle-bar journaled in said head, a needle carried by said needle-bar, a first rotary shaft journaled within said bracket-arm for actuating said needle-bar, a second rotary shaft journaled within said laterally extending arm and operatively connected to said first rotary shaft, a pair of rock-shafts disposed lengthwise of and within said depending arm at opposite sides of said second rotary shaft, said rock shafts each being operatively connected with said second rotary shaft and having its lower end journaled within said downwardly projecting extension, a movable threaded looper complementary to said needle in the formation of chain-stitches, a looper-bar extending lengthwise of said work-supporting arm and carrying said looper, means supporting said looper-bar for pivotal movements about an axis disposed in parallelism with the general direction of needle reciprocation and slidable movement in a fixed plane disposed at right angles to said pivotal axis, a pair of rock-arms of which each is secured at one end to a respective one of said rock-shafts at a location between the upper end of the rock-shaft and said downwardly depending projection, and means operatively connecting each of said rock-arms with said looper-bar for causing the looper, in cooperation with said looper-bar supporting means, to move in a direction parallel to the longitudinal axis of said work-supporting arm during its loop-seizing and loop-shedding strokes.

19. In a feed-off-the-arm sewing machine having a frame provided with an overhanging head and a work-supporting arm having its free end disposed beneath said head, an endwise reciprocatory needle carrying bar journaled in said head and mounted for lateral work-feeding movements in a plane parallel to the vertical plane of the axis of the work-support, means for imparting said lateral work-feeding movements to said nee-

idle-bar, a needle carried by said needle-bar, and stitch-forming mechanism in said work-supporting arm complementary to said needle in the formation of chain-stitches, said stitch-forming mechanism including a thread-carrying looper having loop-seizing movements in a direction opposed to the work-feeding movements of the needle and loop-spreading movements laterally of the line of the work-feeding movements of the needle, a spreader cooperating with said looper and having movements transversely of the work-feeding movements of the needle in a direction opposite to the loop-spreading movements of said looper, said looper and spreader thereby operating to form a thread-triangle for entrance by the needle, and mechanism extending lengthwise through said work-arm for actuating said looper and spreader in timed relation with the endwise and sidewise movements of said needle.
